UNITED STATES PATENT OFFICE.

ALFRED H. HUMPHREY, OF NEW YORK, N. Y.

GAS-COCK-OPERATING DEVICE.

1,026,039.

Specification of Letters Patent.

Patented May 14, 1912.

Application filed August 25, 1910. Serial No. 578,884.

REISSUED

To all whom it may concern:

Be it known that I, ALFRED H. HUMPHREY, a citizen of the United States, and a resident of the city, county, and State of 5 New York, have invented certain new and useful Improvements in Gas-Cock-Operating Devices, of which the following is a specification.

My invention relates to that class of device in which illuminating gas may be turned on and off by the simple pulling of a depending chain or cord,—each downward pull turning the gas-cock one quarter around so that alternate pulls open and close the 15 cock. It is preferably applied to that style of gas jets in which a pilot flame is kept constantly burning so that the gas may ignite as soon as it is turned on.

The object of my invention is to provide 20 a simple, durable, and sightly, gas-cock operating device which will not readily get out of order and which can be easily applied and removed from the gas jet if occasion requires.

25 In the accompanying drawings:—Figure 1, is a front elevation. Fig. 2, is a vertical section on line 2—2, of Fig. 1. Fig. 3, is a section on line 3—3 of Fig. 2. Fig. 4, is a plan view of the chain wheel or pulley. 30 Fig. 5, is a detail of the spring friction disk against which the chain wheel bears with proper tension and serves as a clutch to cause the cock to turn when the chain is pulled.

35 Same letters indicate similar parts in the different figures.

A, represents a fitting or cock-body of usual construction, provided with the spring-mounted tapering plug B, with the channel 40 a, adapted to allow gas to pass from the inlet b, to the jet opening c, when in the position shown in Fig. 2.

C, is an adjustable pilot flame fixture of usual construction.

45 D, is an open shell formed as a projection on the body of the gas-cock A, to serve as a support and gripping device for the removable shell E. These two shells form a casing in which the cock-turning devices 50 are placed and by which they are covered and practically protected from dust, moisture, and all outside interference,—the operating chain passing through a bell-shaped tube d. These two parts of the casing are

preferably telescoped, the removable portion being simply held by the pressure of the fixed portion, but they may be otherwise interlocked or fastened, if preferred.

The stem e, of the cock B, is internally screw-threaded to receive the screw f, which fastens the spring-friction disk F to the stem e,—said disk having a central opening m, with a squared side n, which fits a squared shoulder on the stem e, so that when the disk is turned the stem is also turned to open or close the cock. This friction disk F, has a number of notches or slits running in from the circumference, the metal being slightly turned as shown in the drawing to form small friction ridges which secure sufficient hold upon the chain wheel to turn it when the chain is pulled but lose this hold when the chain is released. The chain wheel G, is loosely mounted on the stem e, and is held against the friction disk by the coiled 75 spring H, which surrounds said stem. One end of the spring is inserted in a hole h, in the body of the fixture A, while the other end is held in one of the three holes g, g, g, of the chain wheel G, (see Fig. 4). The 80 balls of the chain J, lie in the grooved periphery of the wheel G,—one of the balls being caught in the fork j.

The swing of the chain wheel, is limited to a quarter circle by the lugs k, k, which 85 come against the fixed stop l, downwardly projecting on the inside of the shell D. The chain wheel is normally held in the position shown in Fig. 3 by the pull of the coiled spring H. The friction exerted when the 90 chain is pulled is sufficient to make the disk F turn with the wheel, but the configuration of the disk is such that it does not press against the wheel with sufficient force to prevent the wheel from turning back freely 95 when the chain is released. When the chain is released the chain wheel turns back a quarter circle but does not carry the stem e, with it as the spring-mounted plug exerts sufficient friction to prevent.

100 The operation of my improved device will, I think, be readily understood without further description.

I claim:—

1. A gas-cock operating device consisting 105 of suitable devices, mounted upon the cock-stem, whereby the cock is opened and closed as desired, and an inclosing shell consisting

of a sliding section and a stationary section mounted upon a projection of the gas-jet-body adapted to grip and support said sliding section.

5 2. A gas-cock operating device which consists of a notched friction disk mounted on the end of the cock-stem, a chain wheel

loosely mounted on said stem and a shell adapted to cover and protect the same and supported by the gas-jet-body.

ALFRED H. HUMPHREY.
